UNITED STATES PATENT OFFICE.

FRED. L. MANNY, OF BENTON HARBOR, MICHIGAN, ASSIGNOR TO BAKER-VAWTER COMPANY, OF BENTON HARBOR, MICHIGAN, A CORPORATION OF MICHIGAN.

DEVICE FOR FORMING POSTING-SLIPS.

1,379,411.

Specification of Letters Patent.

Patented May 24, 1921.

Application filed October 2, 1917. Serial No. 194,350.

To all whom it may concern:

Be it known that I, FRED. L. MANNY, a citizen of the United States, residing at Benton Harbor, in the county of Berrien 5 and State of Michigan, have invented certain new and useful Improvements in Devices for Forming Posting-Slips, of which the following is a specification.

In keeping books of accounts of business 10 transactions it is in many cases desirable, while entering a list of items on consecutive lines of a single sheet, to make duplicate or manifold copies of the items individually, so that they may be distributed 15 and posted in several different ledgers, or other account books, by different book-keepers at the same time. This cannot be done by cutting apart the separate items of an ordinary impression copy, since the slips 20 are entirely too narrow and slender for convenient handling. The object of my present invention is the provision of a mechanical device whereby a copy may be conveniently made of each individual item as it is 25 entered, of proper size for convenient use as a posting slip, and my invention consists in the combination, arrangement and construction of coöperating parts which constitute my novel device, the essential elements of which are pointed out in the appended claims.

Of the drawing, Figure 1 is a perspective view of my device; Fig. 2 is a vertical section on the line 2—2 of Fig. 1, partly in 35 elevation, showing the mounting of the paper-roll guide; Fig. 3 is a fragmentary top view of a corner of the device; Fig. 4 is a section on the line 4—4 of Fig. 3; Fig. 5 is a fragmentary top view of the tearing 40 clip and guides at the right hand edge of the device; and Fig. 6 is a cross-section on the line 6—6 of Fig. 1, illustrating the same parts as are shown in Fig. 5.

The same reference characters indicate 45 the same parts in all the figures of the drawing.

The platen 1 of my device is provided with spring clips 2 by means of which the entry sheet 3 and sheet of impression paper 50 4 are held in place thereon for writing. In the present instance these clips are riveted to corner brackets 5 at the upper and lower lefthand corners of the platen, the base portions 5^a of which brackets are counter-sunk in the platen flush with the upper sur-

face thereof, and gage studs 6 are secured to the bases 5^a to provide for accurate positioning of the paper. Means for simultaneously releasing the clips 2 are provided, consisting of a rod 7 journaled in the 60 brackets 5 and formed with bends 7^a which, when the rod is turned by an operating knob 8, engage the clips and lift them out of engagement with the paper on the platen.

Rotatably mounted on a rod 9 which extends between the upper ends of the brackets 5 parallel with the lefthand margin of the platen is a roll of paper 10, the free end of which passes between the side members 11^a of a sheet metal paper-roll guide 11, and 70 across the platen underneath the sheet of impression paper 4, to and under a guide and tearing clip 12 at the righthand edge of the platen. The side members 11^a of the paper-roll guide 11 are orificed to engage the 75 rod 9 and formed with slots which receive the rod 7, and the fitting of the parts is such that the inherent resiliency of the sheet metal and rods will afford a yielding frictional resistance to displacement. The inner 80 lower edge of the guide is slightly curved and while not urged downward by spring pressure assists in a measure in keeping the sheets of paper smooth and flat upon the platen. 85

To provide for replacement of the paper-roll, the ends of the rod 9 are of reduced diameter, forming short gudgeons 9^a which engage sockets in the brackets 5. These brackets are of sufficiently flexible and resili- 90 ent metal to permit them to be bent side- wise out of engagement with the pivots, when the rod, with this paper-roll guide attached, may be removed, and a fresh roll substituted. 95

At the right hand side of the platen is arranged a bar 13 (in the present instance corrugated to increase its stiffness) upon which is slidingly mounted the guide 12 before mentioned. The end of the paper 10 passes 100 under this guide and between two downwardly-bent tongues which curve downwardly against the side of the platen, the metal between the tongues being extended upwardly and outwardly to form a tearing 105 blade 14. As shown the edge of the blade is inclined so that when a section of the paper, as long as the width of the entry sheet, which is to be detached, is drawn sharply across the blade, to the left and somewhat back- 110

wardly, the blade will cut into the upper edge of the paper and the tear follow the line of the blade thereacross.

The strip of paper 10 is preferably of 5 about the width of five writing lines upon the entry sheet, and if desired the entry sheet may be ruled with distinguishable lines at intervals corresponding to the width of the strip 10, this strip being of such width 10 as to form posting strips of convenient size when torn off as above described.

With the foregoing explanation of the construction of my device, the manner in which it is used will readily be understood. 15 The entry sheet and impression paper are inserted under the clips and over the paper strip 10, with the guides 11 and 12 so adjusted that such strip will underlie the uppermost line on the entry sheet. After 20 each entry of an item the strip 10 is drawn out the width of the entry sheet and torn off, and from time to time the guides shifted downwardly so that the strip 10 will always be beneath the lines of the entry sheet as 25 they are written upon. Obviously, if the strip is of such width as to underlie five writing lines of the entire sheet, the guides need be shifted only after every five entries; but if desired they may be adjusted and 30 shifted in such manner that the impression on the posting slip will always be at the center line thereof.

It is obvious that my invention is applicable to any loose-leaf system of records or 35 account books in which it is desired to produce separate copies of convenient size of any series of items entered on consecutive lines of a single sheet, and that these copies are available for immediate distribution and 40 use as fast as they are made.

I claim:

1. A device for forming posting slips comprising a platen arranged to support an entry sheet and an impression sheet, a rod 45 adjacent the left hand margin of the margin of said platen, a second rod mounted on said platen adjacent said first-mentioned rod, said second rod being arranged to support a paper roll slidingly mounted thereon, a sliding 50 guide engaging said rods and arranged to also engage said paper roll, and guide means adjacent the right hand margin of the platen for supporting the end portion of the paper of said roll transversely of the entry 55 sheet.

2. A device for forming posting slips comprising a platen arranged to support an entry sheet and an impression sheet, a rod mounted on said platen adjacent and parallel with one side thereof, said rod being arranged to support a paper roll mounted to slide axially thereon, and guide means on opposite sides of the platen for supporting the end portion of paper of said roll trans- 60 versely of the entry sheet.

3. A device for forming posting slips comprising a platen, paper-holding means for securing an entry sheet and impression sheet to said platen comprising a manually operable rod adjacent one margin of said platen 70 and means co-operatively connected therewith for securing and releasing said sheets, a second rod mounted on said platen parallel with said first-mentioned rod, said second rod being arranged to support a paper roll 75 mounted thereon, a sliding guide frictionally engaging said rods and also arranged to engage said paper roll, and a guide for the paper of the roll slidingly mounted on said platen adjacent its opposite margin. 80

4. A device for forming posting slips comprising a platen, paper-holding means for securing an entry sheet and impression sheet to said platen comprising a manually operable rod adjacent one margin of said platen 85 and means co-operatively connected therewith for securing and releasing said sheets, a second rod mounted on said platen parallel with said first-mentioned rod, said second rod being arranged to support a paper roll 90 mounted thereon, a sliding guide frictionally engaging said rods and also arranged to engage said paper roll, and a guide for the paper of the roll slidingly mounted on said platen adjacent its opposite margin, said 95 guide being formed with a tearing blade.

5. A device for forming posting slips comprising a platen, paper-holding means for securing an entry sheet and impression sheet to said platen comprising a manually operable rod adjacent one margin of said platen 100 and means co-operatively connected therewith for securing and releasing said sheets, a second rod mounted on said platen parallel with said first-mentioned rod, said second 105 rod being arranged to support a paper roll mounted thereon, a sliding guide formed with orificed side members engaging said second rod on opposite sides of the paper roll and also slidingly engaging said first-mentioned rod, and a guide for the paper of the roll slidingly mounted on said platen adjacent its opposite margin. 110

6. A device for forming posting slips comprising a platen, paper-holding means for securing an entry sheet and impression sheet to said platen comprising a pair of spring clips respectively mounted adjacent the upper and lower corners of said platen at one side thereof, and also comprising a manually operable rotatable rod parallel with said margin and formed with bends engaging said clips, a second rod mounted on said platen parallel with said first-mentioned rod, said second rod being arranged to support 120 a paper roll mounted thereon, and guide means for supporting the end portion of the paper of said roll transversely of the entry sheet. 125

7. A device for forming posting slips com- 130

- prising a platen arranged to support an entry sheet and an impression sheet, a rod mounted on said platen adjacent and parallel with one side thereof, said rod being arranged to support a paper roll mounted to slide axially thereon, a bar secured at its ends to said platen adjacent the opposite side thereof, and a clip slidingly mounted on said bar and formed with depending tongues arranged to engage opposite sides of the strip of paper of the roll and with an intermediate outstanding tearing blade.
5. In a device of the character described, a
10. platen, a pair of spring-metal brackets secured thereto adjacent the upper and lower corners at one side margin thereof, a rod having gudgeons mounted in said brackets, a second rod mounted on said platen below said first-mentioned rod and adjacent said side margin of the platen, and a paper-roll 15 guide having side members formed with orifices engaging said first-mentioned rod and with slots slidably engaging said second-mentioned rod.

8. In a device of the character described, a

FRED. L. MANNY.
